UNITED STATES PATENT OFFICE.

LAWRENCE W. MAMMEN, OF CHICAGO, ILLINOIS.

ORNAMENTAL LIGHT.

Application filed June 1, 1926. Serial No. 112,805.

My invention relates to an ornamental light more especially intended for decorative purposes; the invention contemplating a light made in semblance of a star.

5 The object of my invention is the provision of an electric light constructed so as to provide light beams radiating in the manner of the rays of a star.

10 The objects and advantages of my invention will be more readily comprehended from the detailed description of the accompanying drawings, wherein:

Figure 1 is a sectional elevation of one form of my improved light.

15 Figure 2 is a side elevation thereof.

Figure 3 is a cross sectional view taken on the line 3—3 of Figure 1.

Figure 4 is a sectional elevation of a modified form.

20 Figure 5 is a side elevation of the modification shown in Figure 4.

Figure 6 is a sectional view taken substantially on the line 6—6 of Figure 4.

25 My improved ornamental light as shown in the first three figures of the drawings comprises the side walls 10, 10 similar in construction and configuration and preferably composed of a translucent material, such as suitably coated or ground glass 30 moulded into proper shape to provide the various star points 11. The sloping sides of the various points 11 are provided with openings as at 12, while the inner or opposing faces of the two side walls, in the point portions thereof, are formed with the outwardly bulging or sloping portions 13 arranged to provide openings 14 disposed generally in the direction of the points 11 in order that the light emitted by the openings 40 will be directed radially outward in the semblance of the rays of a star.

The side walls 10, 10, at points below the bases of the point portions are each formed with a circumferential rim or flange 15, 45 with the flanged sides of the complementary members disposed toward each other. The flange portions 15 maintain the side walls 10, 10 in suitable spaced relation thereby providing a chamber between the two sides 50 and within the abutting rims for the reception and mounting of the electric bulbs shown at 16 and 17.

The flange portions 15, 15 are encircled by a suitable band 18, which may be of sheet metal formed to snugly fit about the flanges

and have holding relation therewith to maintain the side walls 10, 10 in place. The ends of the band 18 are shown secured in Figure 1 by means of small screws 19 to a flange formed on the stem portion 20 of an 60 inner concentric band 21 within which is mounted a third concentric band 22 in slight spaced relation with band 21. The two bands 21 and 22 are shown secured to an insulating plug 23 which also extends into the 65 stem portion 20; the insulating plug 23 as well as the respective socket members 24 secured on the inner band 22 maintain the proper spaced relation between the two bands 21 and 22; while the stem portion 70 20 maintains the proper relation between the inner concentric bands 21 and 22 and the outer band 18. The stem portion 20 is also adapted to receive a plug member 25 adapted to form proper electrical connection with the terminal points 26 arranged within plug member 23; the terminals 26 being in turn wired to the respective lamp holding socket members 24 and the inner socket member 27 as shown at 28 in Figure 1, so that all of the 75 80 bulbs within the light may receive current from a single lead or supply line 29.

The outer band 18 is shown provided along its circumferential center line with a plurality of openings or slots 30; and the band is also shown provided with smaller openings preferably arranged at prearranged spaced points apart as shown for example at 31 and registering with similar holes made in the rims or flanges 15, 15 in order that 85 light may be emitted through the openings in the opaque band in the form of defined rays.

The band 21 is employed for the purpose of rigidly holding the various socket members 24 and light bulbs 17 in place. This band, however, may be omitted if the inner band 22 is made of sufficiently strong material. The filament holding portion of the light bulb 16 is shown preferably disposed substantially at the center of the star or light, while the bulbs 17 are disposed at points coincident with the star points.

In Figures 4 to 6, I show a modified form 95 with the side walls 32, made of any suitable translucent material or translucent glass; the side walls being moulded to provide any suitable number of star-points or portions 100 33; while the opposing faces of the side members are provided with the circumfer- 110

ential flanges 34, substantially similar to the construction shown in Figure 1. The circumferential flanges 34 are encircled by a band 35, preferably of sheet metal, snugly fitted about the flange portions 34 so as to hold the sides 32, 32 in juxtaposition. The band 35, at points coincident with the valleys intermediate of the points 33 of the two outer side walls 32, is provided with 10 openings at 36 surrounded by the outwardly disposed converging walls 37 which may be formed by stamping the sheet metal band. Arranged concentrically within the band 35 is a band or ring member 38 which is 15 preferably dished or concaved in cross-section as shown in Figure 6. A plurality of lamp-holding sockets 39 and 40 are mounted on the band 38; the sockets 39 being disposed on the outer dished side, while the 20 sockets 40 are arranged on the inner perimeter of the band 38, see Figure 4. Dishing the band 38 as shown permits the same to be used in the nature of a reflector for the light emitted by the bulbs 41 and causes the same 25 to be reflected toward the openings 36, coincident with which bulbs 41 are mounted. The inner band 38 is maintained in proper concentric spaced relation with the flanges 34 of the main side walls and therefore also 30 with the outer band 35, by the insulating block 42 to which the inner band 38 is secured as for example by the screws or bolts 43. The block 42 is provided with suitable terminals 44 adapted to receive the usual 35 connecting plug 45 attached to the end of the lead line or wire 46. The various bulbs are all electrically connected by suitable wiring as at 47 in Figure 4 so as to permit a single lead line to be employed. The bulb-holding 40 sockets 39 and 40 are preferably arranged in the staggered relation shown in Figure 4 on the outer and inner perimeters of the band 38; and it will be understood, of course, that colored bulbs may be employed 45 for the sockets 40 if desired, while white bulbs are employed in the sockets 39 so as to transmit bright rays through the openings 36.

These lights may be secured or suspended 50 in place in any suitable manner, and any number of small filament bulbs may be employed to properly illuminate the entire side walls of the light and also to provide the light-rays through the openings; and while 55 I have shown certain exemplification of my invention, it will be understood, that modifi-

cations may be made without, however, departing from the spirit of my invention.

What I claim is:

1. An ornamental light in the nature of 60 an illuminated star composed of a pair of complementary star shaped members of translucent material formed at the points with double walls in spaced relation, the inner walls of both members at the base of the 65 points each having a laterally disposed annular flange, a band encircling the flanges for holding the members together in spaced relation, said band being provided with an electric plug and lamp holding socket. 70

2. An ornamental light in the nature of 75 an illuminated star composed of a pair of complementary star shaped members of translucent material formed at the points with double walls, the inner walls of both 80 members at the base of the points each terminating in a laterally disposed annular flange, a band encircling the flanges for holding the members together, said band at circumferentially spaced points having defined 85 openings for the outward passage of the light and being provided with an electric plug and lamp holding socket.

3. An ornamental light in the nature of 90 an illuminated star composed of a pair of 85 complementary star spaced members of translucent material formed at the points with spaced double walls, the inner walls of both members at the base of the points each terminating in a laterally disposed annular 95 flange, the double walls of the star points being provided with openings for passage of light-rays therethrough, a band encircling the flanges for holding the members together and provided with an electric plug and 100 lamp-holding socket.

4. An ornamental light in the nature of 105 an illuminated star composed of a pair of complementary star shaped members of translucent material formed at the points with spaced double walls, the double walls of the star points being provided with openings for passage with the light-rays, the inner walls of both members at the base of the points terminating in laterally disposed 110 annular flanges, a band encircling the flanges for holding the members together and provided with an electric plug holding socket, and an inner concentric band provided with 115 bulb holding sockets.

LAWRENCE W. MAMMEN.
